CLAIM

The ornamental design for a coating material dispensing device, as shown and described.

DESCRIPTION

FIG. 1 illustrates a right side elevational view of an embodiment of a coating material dispensing device showing our new design, with the left side elevational view being a mirror image of FIG. 1;

FIG. 2 illustrates a top plan view of the coating material dispensing device illustrated in FIG. 1;

FIG. 3 illustrates a front elevational view of the coating material dispensing device illustrated in FIGS. 1-2;

FIG. 4 illustrates a rear elevational view of the coating material dispensing device illustrated in FIGS. 1-3;

FIG. 5 illustrates a bottom plan view of the coating material dispensing device illustrated in FIGS. 1-4;

FIG. 6 illustrates a right side elevational view of another embodiment of a coating material dispensing device showing our new design, with the left side elevational view being a mirror image of FIG. 6;

FIG. 7 illustrates a top plan view of the coating material dispensing device illustrated in FIG. 6;

FIG. 8 illustrates a front elevational view of the coating material dispensing device illustrated in FIGS. 6-7;

FIG. 9 illustrates a rear elevational view of the coating material dispensing device illustrated in FIGS. 6-8;

FIG. 10 illustrates a bottom plan view of the coating material dispensing device illustrated in FIGS. 6-9;

FIG. 11 illustrates a fragmentary right side elevational view of another embodiment of a coating material dispensing device showing our new design, with the left side elevational view being a mirror image of FIG. 11;

FIG. 12 illustrates a fragmentary top plan view of the coating material dispensing device illustrated in FIG. 11;

FIG. 13 illustrates a front elevational view of the coating material dispensing device illustrated in FIGS. 11-12;

FIG. 14 illustrates a rear elevational view of the coating material dispensing device illustrated in FIGS. 11-13; and,

FIG. 15 illustrates a fragmentary bottom plan view of the coating material dispensing device illustrated in FIGS. 11-14.

The claimed design is shown fragmented in FIGS. 11-15 to indicate indeterminate length.
